LAMP FOR SEWING MACHINES

Alphonse Lordo, St. Louis, Mo., assignor to Dazor
Manufacturing Corp., St. Louis, Mo., a corpora-
tion of Delaware

Application January 28, 1952, Serial No. 18,265

Term of patent 14 years

(Cl. D48—20)

To all whom it may concern:

Be it known that I, Alphonse Lordo, a citizen of the United States, residing in the city of St. Louis and State of Missouri, have invented a new, original, and ornamental Design for a Lamp for Sewing Machines, of which the following is a specification, reference being had to the accompanying drawing, forming a part thereof.

In the drawing:

Fig. 1 is a plan view of a lamp for sewing machines, showing my new design;

Fig. 2 is a side elevational view thereof;

Fig. 3 is a front view thereof, and

Fig. 4 is an enlarged fragmentary sectional view taken at line 4—4 of Fig. 2.

I claim:

The ornamental design for a lamp for sewing machines, substantially as shown.

ALPHONSE LORDO.
